UNITED STATES PATENT OFFICE.

EDWIN F. SMITH AND EMIL A. BRINER, OF PHILADELPHIA, PENNSYLVANIA, ASSIGNORS TO EDWIN F. SMITH COMPANY, OF PHILADELPHIA, PENNSYLVANIA, A CORPORATION OF NEW JERSEY.

STAY-LOG.

No. 828,065.

Specification of Letters Patent.

Patented Aug. 7, 1906.

Application filed June 3, 1905. Serial No. 263,580.

To all whom it may concern:

Be it known that we, EDWIN F. SMITH and EMIL A. BRINER, citizens of the United States, residing at Philadelphia, in the county of 5 Philadelphia and State of Pennsylvania, have invented certain new and useful Improvements in Stay-Logs, of which the following is a specification, reference being had therein to the accompanying drawings, forming a part 10 thereof.

Our invention relates to stay-logs or log-carriers for slicing or veneer-cutting machines, and has for its objects economy of material in the slicing or cutting operation 15 and utilization of material heretofore discarded and also ease and rapidity of insertion and attachment of logs or sections thereof, simplicity and economy of construction, and effectiveness of operation. 20 In the work of slicing and cutting veneer and thin stuff as at present carried on a great amount of valuable lumber is discarded as unfit for the cutting or slicing operation, not only the cores, which have been cut down as 25 far as practicable in the usual rotary cutters, but also the logs or timber of comparatively small diameter and which are too small for the rotary cutting-machines. Although numerous stay-logs have been heretofore devised 30 for the half-rotary cutting operation, wherein a section of a log is supported and rotated on an axis exterior to the log-section, these stay-logs have been of limited use and not adapted for gripping small logs or cores, 35 and the great waste of valuable lumber above referred to has not been prevented by the use of any such contrivances.

Our invention aims to provide a stay-log 40 which will readily grip and hold all pieces of lumber, whether round logs, cores, half-sections, quarter-sections, or of any irregular shape and which will rotate these logs or sections so that they may be acted upon by cutting or slicing knives and the veneer or 45 thin stuff cut therefrom, thereby permitting the utilization of any core or small log containing sufficient material and also producing thin material or veneer with a quartered cut, and thus of the most valuable kind as contrasted with the cut produced by the rotation 50 of a log on its own axis, such cut being circumferential to the log and of inferior grain and appearance.

We will now describe the stay-log embodying our invention illustrated in the accompanying drawings and will thereafter point out our invention in claims. 55

Figure 1 is a side elevation, partly in section, on a plane indicated by the line 1-1, Fig. 2. Fig. 2 is an end elevation of the same, 60 showing three logs clamped therein and partly cut. Fig. 3 is an enlarged sectional view of the upper part of the stay-log, taken in a plane indicated by the line 3, Fig. 1.

Upon both ends of a shaft 1, which may be 65 hollow, as shown, the end hubs 2 and 3 are tightly fitted, as by screwing them over the ends of the shaft, as shown. The hubs 2 and 3 are provided with tapering rectangular bores, as usual, to permit the stay-log to be 70 carried by the rotating centers of a slicing or cutting machine.

End spiders 4 and 5 are provided, each shown as consisting of an outer and inner rim and arms joining the two rings, and the 75 inner rims are shown as bolted to the end hubs. In the construction shown, wherein three clamps are provided, each spider is provided with six arms, and to each alternate arm and its adjacent portion of the outer 80 ring a fixed clamping-frame 10 is secured, as by bolts, as shown, this clamping-frame consisting of an L-shaped beam running the full length of the distance between the spiders and with end flanges 11 for the bolts, whereby it is secured at each end to one of the 85 spiders. The fixed clamping-blade 14 of each clamp is set into a recess in the outer face of its fixed clamping-frame and is suitably secured therein, as by countersunk 90 screws, as shown in Fig. 3, and the outer face of the blade is flush with the outer face of the clamping-frame. The gripping edge of this fixed clamping-blade is shown as provided with square-shaped teeth 15, which are 95 equidistantly spaced along the entire length of its gripping edge.

The moving clamping-blades 16 are of the same construction as the fixed clamping-blades 14 and are similarly set with a flush 100 finish into recesses in the movable clamping-frames 17. Each movable clamping-frame 17 extends substantially the full distance between the inner faces of the spiders, with sufficient clearance, however, for freedom of 105 movement, and is carried by radial arms, to

which it is shown as secured by bolts, these arms for each clamping-frame consisting of two end arms 19 and two medial arms 18, each arm having its own hub 20 and the twelve separate hubs for the twelve arms of the three clamping-frames being loosely and independently fitted to rotate upon the central shaft 1. Between the two intermediate arms of each movable clamping-frame a threaded pivot-block 22 is located, the ends of this pivot-block entering bearings in the arms. A clamping-screw 23, provided at one end with a right-hand screw-thread and at the other end with a left-hand screw-thread is shown as provided for each clamp arranged with its left-hand screw-threaded part engaged in the pivot-block 22 and its right-hand screw-threaded part engaged in another pivot-block 27, which is pivoted in bearings provided by the adjacent faces or brackets 30, which are bolted to the fixed clamping-frame 10. An opening 26 is provided in each fixed clamping-frame for the free passage of the clamping-screw 23, and the clamping-screw 23 is shown as squared at its end for convenient operation. By reason of the provision of right and left threads the rotation of each clamping-screw will cause its movable clamping-frame to approach to or recede from its fixed clamping-frame, thereby opening or closing the jaws formed by the clamping-blades 14 and 16.

A back support or rest is provided for each clamp coöperative with the clamping-jaws and adjustable to nicely determine the gripping-points of the clamping-jaws. Each of these adjustable back supports consists of a beam-shaped casting 32, which extends longitudinally almost the entire distance between the spiders and has a flat face bearing against the adjacent side face of the fixed clamping-frame 10 and has an outer face arranged angularly thereto and tangentially to a circumference described from the center of rotation of the stay-log, these two faces being upon angular flanges which are braced at intervals by strengthening-ribs and the flange which bears against the side face of the stationary clamping-frame being partly cut away to save weight and also to provide clearance for the clamping-screw 23 and also tapering toward its ends to economize material without sacrifice of strength. Adjustment-screws 33 enter threaded bosses of the back supports and are fitted to rotate in bearing-blocks 38, which are shown as provided with pivotal connections with the fixed clamping-frames, the pivotal connection for each bearing-block 38 being provided by a pivot-pin 39, projecting from the bearing-block and passing through the fixed clamping-frame and having a nut bearing against the opposite face of the fixed clamping-frame. (See Fig. 3.) The inner end of each adjust-

ment-screw 33 is provided with a hand-wheel 65 40, fixed thereon. The boss of each hand-wheel 40 bears against one face of its bearing-block 38, and the screw has an enlargement or collar 41, which bears against the opposite face of its bearing-block 38, so as to prevent end movement of the adjustment-screw and so that the rotary movement of the hand-wheel will cause the back support to be thrust inward or outward. Two adjustment-screws are shown as provided for each back support 32, and the pivotal connections of their bearing-blocks permit one to be advanced ahead of the other without jamming.

In the operation of the machine the logs or sections of logs are most conveniently inserted with the clamping-jaws in their upper position, as the log or section may then be laid upon the back support 32 and the back support adjusted by manipulation of the hand-wheels 40 so as to bring the log or section in proper position for the clamping of the log or section, so as to permit the greater part or the desirable part of the log or section to be sliced, and thus the clamping-points may be nicely determined by the adjustment of the back support. Thereafter the clamping-screw 23 is actuated to cause the clamping-jaws to close and to firmly grip the log or section between the clamping-blades. The other two clamps may then be similarly provided with logs or sections of logs, and the slicing operation may then be carried on in the usual manner by rotating the entire stay-log, so as to effect orbital revolution of the clamping-jaws and the logs held thereby. The slicing operation may be continued until the wood has been sliced off down to the clamping-jaws, thus permitting the utilization of practically all of the desirable part of the lumber.

It is obvious that various modifications may be made in the construction shown and above particularly described within the principle and scope of our invention.

What we claim, and desire to secure by Letters Patent, is—

1. A stay-log adapted to receive rotary motion and comprising orbitally-revolvable clamping-jaws, an adjustable back support coöperative with the clamping-jaws and rotatable with the clamping-jaws, and means for moving the clamping-jaws toward each other in a direction transverse to their axis of revolution to grip the work laterally.

2. A stay-log adapted to receive rotary motion and comprising two clamping-jaws, one of which is pivotally mounted at the axis of rotation of the stay-log, and means for moving the clamping-jaws toward each other to grip the work.

3. A stay-log adapted to receive rotary motion and comprising a clamping-jaw fixed thereon, another clamping-jaw pivotally

mounted at the axis of rotation thereof, and means for moving the clamping-jaws toward each other to grip the work.

4. A stay-log adapted to receive rotary motion and comprising two clamping-jaws, one of which is pivotally mounted, an adjustable back support coöperative with the clamping-jaws, and means for moving the clamping-jaws toward each other to grip the work.

5. A stay-log adapted to receive rotary motion and comprising a clamping-jaw fixed thereon, an adjustable back support slidably movable thereon, another clamping-jaw pivotally mounted at the axis of rotation of the stay-log, and means for moving the clamping-jaws toward each other to grip the work.

6. The combination of a clamping-frame rotatably mounted and a clamping-jaw thereon, a back support slidably movable upon the clamping-frame, means for adjusting the back support, another clamping-frame pivotally mounted relatively to the first-mentioned clamping-frame and a clamping-jaw thereon, and means connecting the clamping-frames for moving the jaws toward each other to grip the work.

7. The combination of end pieces adapted to engage rotating centers, a plurality of clamping-frames secured to the end pieces, 30 clamping-jaws upon the clamping-frames, back supports slidably movable upon the clamping-frames, means for adjusting the back supports, a central shaft secured to the end pieces, clamping-frames pivotally mounted upon the central shaft, clamping-jaws upon the pivotally - mounted clamping-frames, and means connecting the clamping-frames for moving the jaws toward each other to grip the work, substantially as described. 35

8. A stay-log adapted to receive rotary motion and comprising a plurality of pairs of clamping-jaws and means for moving the clamping-jaws toward each other to grip the work, one clamping-jaw of each pair being 40 pivotally mounted at the axis of rotation of the stay-log.

In testimony whereof we have affixed our signatures in presence of two witnesses.

EDWIN F. SMITH.
EMIL A. BRINER.
